UNITED STATES PATENT OFFICE.

HARRY M. WALKER, OF ELLENTON, SOUTH CAROLINA.

CENTERING-PUNCH.

1,351,592.

Specification of Letters Patent. Patented Aug. 31, 1920.

Application filed November 29, 1919. Serial No. 341,555.

To all whom it may concern:

Be it known that I, HARRY M. WALKER, a citizen of the United States, and a resident of Ellenton, in the county of Aiken and 5 State of South Carolina, have invented certain new and useful Improvements in Centering-Punches, of which the following is a specification.

My invention is an improvement in 10 centering punches, and has for its object to provide a device of the character specified, having means in connection therewith for permitting the punch to be accurately centered in an opening of a pattern plate for 15 instance, to insure that the punch will engage the work at the exact center of the opening desired to be made, and wherein the punch is adjustable for openings of various sizes.

20 In the drawings:—

Figure 1 is a front view of the improved punch in use,

Fig. 2 is a vertical section,

Fig. 3 is a section on the line 3—3 of 25 Fig. 2,

Fig. 4 is a perspective view of one of the centering blades.

The improved punch comprises a body 1 of cylindrical form, having its lower end 30 pointed as shown at 2, and this body is provided intermediate its ends with a series of longitudinally extending grooves 3, three grooves being provided in the present instance, and the said grooves are spaced apart 35 from each other at intervals of 120°.

A centering blade 4 is pivoted in each groove, by means of a pivot pin 5 which passes through registering openings in the side walls of the groove and in the blade, 40 and each blade at its upper end is normally pressed away from the body of the punch by means of a plate spring 6. Each of these springs 6 is secured to the blade at its top, and has an angular portion at its free end, 45 which bears against the bottom of the groove.

Each blade is of angular formation, as clearly shown in Figs. 2 and 4, comprising a relatively long portion and a relatively 50 short portion extending at an obtuse angle with respect to each other, and the free end of the short portion is bent outwardly as shown at 7 to provide an engaging surface for engaging the inner wall of the 55 opening 8 of the pattern 9.

A collar 10 encircles the body at the pivotal connection of the blades, it being understood that all the blades are pivoted at the same point in the length of the body, and this collar is movable on the body, to cause 60 the lower ends of the blades to project more or less beyond the periphery of the centering punch. The upper end of the punch, that is, the end remote from the point 2 is formed into a head 11 as shown, for engagement by a hammer or the like to cause 65 the punch to mark the work indicated at 13.

The collar 10 as shown more particularly in Fig. 3 has a notch or recess 12 at each blade, in which a portion of the blade fits, 70 and angular movement of the collar is thus prevented. The blades are so formed that when the spring 6 is fully expanded, the lower end of the blade, that is, that portion below the pivotal connection will lie close 75 in the groove.

In operation the pattern 9 which may be of course the work which has already been punched, is laid upon the work 13 to be punched, and properly positioned thereon. 80 Now the punch is inserted in one of the openings 8 of the pattern, and properly centered by means of the blades 4, the said blades being moved inward or outward until the lower end thereof contacts smoothly 85 with the inner wall of the opening 8.

They may be moved simultaneously by means of the collar 10. It will be evident that when the collar is moved upwardly above the points of the blades, the lower 90 ends of the blades will be extended, while when the collar is moved downwardly, the said lower ends will be retracted. When the punch is properly centered, a blow from a hammer or the like on the head of the 95 punch will make the centering opening. Only a light blow of the hammer is necessary.

I claim:—

1. A centering punch comprising a body 100 having at one end a point and at the other a head, and having longitudinally extending grooves spaced apart from each other, a blade of angular formation pivoted in each groove, each blade consisting of a relatively 105 long portion and a relatively short portion extending at an obtuse angle with respect to each other, said short portions extending toward the engaging end of the punch, a spring normally pressing the long portion 110

of each blade away from the body, and a collar movable on the body and the blades for operating the blades.

2. A centering punch comprising a body having longitudinally extending grooves spaced apart from each other, a blade of angular formation pivoted in each groove, each blade consisting of a relatively long portion and a relatively short portion extending at an obtuse angle with respect to each other, said short portions extending toward the engaging end of the punch, a spring normally pressing the long portion of each blade away from the body, and a collar movable on the body and the blades for operating the blades.

3. A centering punch provided with longitudinally extending grooves spaced apart from each other, a centering blade arranged in each groove and pivoted to the punch, each blade being of angular formation and pivoted at the angle thereof, and means for simultaneously swinging the blades on their pivotal connection, said means comprising

a collar movable on the punch and embracing the blades, springs normally acting on the blades to swing the ends of the blades adjacent to the engaging end of the punch inwardly.

4. A centering punch provided with longitudinally extending grooves spaced apart from each other, a centering blade arranged in each groove and pivoted to the punch, each blade being of angular formation and pivoted at the angle thereof, and means for simultaneously swinging the blades on their pivotal connection, said means comprising a collar movable on the punch and embracing the blades.

5. A centering punch provided with longitudinally extending grooves spaced apart from each other, a centering blade arranged in each groove and pivoted to the punch, each blade being of angular formation and pivoted at the angle thereof, and means for simultaneously swinging the blades on their pivotal connection.

HARRY M. WALKER.
